UNITED STATES PATENT OFFICE.

ARTHUR HOUGH, OF DRAGON, QUEBEC, CANADA.

CONDENSER.

1,191,899.

Specification of Letters Patent.

Patented July 18, 1916.

Application filed February 9, 1915. Serial No. 7,204.

To all whom it may concern:

Be it known that I, ARTHUR HOUGH, a resident of Dragon, Province of Quebec, Dominion of Canada, have invented certain new and useful Improvements in Condensers; and I do hereby declare that the following is a full, clear, and exact description thereof.

My invention relates to condensing apparatus and more particularly to apparatus for condensing nitric acid vapor.

In the method to which my invention more particularly relates it is usual to employ apparatus consisting of a plurality of units through a series of which condensation is not only progressively developed but full condensation of a portion of the vapor is usually obtained in each unit.

This invention relates more particularly to the units of the apparatus; and it may be said briefly to consist of a unit comprising a section or container of dish form provided with a cover divided into a number of parts each of which carries a plurality of condensing members fed from and detachably connected to a pair of headers, each connection being adapted to be opened or closed as conditions require. For full comprehension, however, of my invention reference must be had to the accompanying drawings forming a part of this specification in which similar reference characters indicate the same parts, and wherein:

Figure 1 is a plan view of my improved nitric acid condenser unit; Fig. 2 is a longitudinal vertical sectional view thereof taken on irregular line 2—2 of Fig. 1; and Fig. 3 is a detail sectional view taken on line 3—3 of Fig. 1; and Fig. 4 is a sectional view of the means effecting communication between two units.

The dish or container of my unit is indicated at 2 and it is cast in acid resisting material, with an acid-vapor intake (4) at one end and communicating with the interior at approximately midway the depth thereof, and a trapped acid outlet (5) in the bottom at the opposite end, such bottom sloping slightly to such trapped outlet; and an outlet duct 6 for the uncondensed vapor is located at approximately midway the depth thereof, and at the end of the container opposite to the intake 4, both intake and outlet 4 and 6 being disposed in the longitudinal vertical plane of the container. The trapped acid outlet, 5, communicates with any suit-

able acid receiver. The trap, indicated at 25, for the acid outlet duct 5 is preferably bolted to a boss on the bottom of the container and is provided with a valve 26, while 60 feet 27 lift the container sufficiently from its support to accommodate the trap and valve; and the sloping interior of the bottom is provided with a series of ribs 28 longitudinally arranged and increasing progressively in height toward the outlet duct to afford a horizontal support for a perforated false bottom 29 made up of a plurality of transverse sections 50. The intake and outlet, 4 and 6 respectively, are preferably of relatively large capacity and of horizontal elliptical form to facilitate the dispersion of the vapor throughout the full width and height of the container, the flanged construction thereof affording means 75 whereby the connection, 30, between the unit and another unit and the next unit of the series or the still at one side and another unit or the final discharge at the other side. This connection in each case is preferably 80 in the form of an elbow, the upper surface of which is provided with a recess, 31, of greater diameter than the passage therefor, in order to accommodate the outlet or inlet duct, indicated at 32, as the case may be, of 85 the next adjoining unit.

In order to seal the joints between the cover parts and between each of the latter and the protruding ends of the condenser members, each part of the cover is formed 90 with beveled sides, 35, and each end thereof has a pair of transverse ribs or flanges, 36, flanking the series of holes through which the ends of the condenser members protrude. In completing these joints the recesses 95 formed by each adjoining pair of parts and the space between the flanges at each end and consequently surrounding the ends of the condenser sections, are filled with cement. The top or rim of the container is preferably 100 dressed to have a cover fit tightly thereon, such cover being suitably packed or sealed, and it is divided into a number of parts, carrying a plurality of condenser-members.

Each condenser member consists of a preferably six-loop zig-zag coil of glass tubing the loops being substantially equal in height to the interior of the container and resting upon the false bottom, the opposite ends of each coil protruding upwardly through holes 110 in the cover, each part, 7, of which carries three such coils in staggered relation, thus

making twenty-four coils carried by the eight cover pieces, although the particular number of coils may be varied to suit different conditions, but I prefer to use the number stated. These coils are connected to inlet and outlet headers or manifolds 9 and 10, respectively, each equal in sectional area to the sum of the sectional area of the coils, the connection between the ends of the coils and headers or manifolds being effected by a series of nipples, 12, carried rigidly by the latter. These nipples may be provided with taps (13). Pieces of rubber piping (14) connect the ends of the nipples to the top of the coils. The taps (13) permit the condensing action to be regulated and at the same time permit a coil to be removed when damaged and a new one substituted without stopping the operation of the apparatus. The advantage of the zigzag nature of the coils is that it imparts flexibility to them thereby reducing danger of breakage from expansion and contraction to a minimum; while the fact that the coils are in staggered relation breaks any direct flow of the vapor from intake to outlet.

When in operation water is caused to flow from inlet header 9 through the coils to outlet header 10 and the nitric acid vapor flows from the intake 4 through the container, between the loops of the condenser-members, to the outlet 6, the portion of the vapor which is condensed dropping to the bottom and flowing out through trapped outlet 5.

What I claim is as follows:

1. A condenser unit for nitric acid vapor, comprising a container of dish form, consisting of acid resisting material having an intake and an outlet for the vapor to be condensed and a trapped outlet in the bottom thereof for the liquid acid; a cover divided into a plurality of parts; a series of condenser-members carried by the cover parts and having their ends protruding therethrough; a pair of inlet and outlet headers connecting with the opposite ends of the condenser members and from which a condensing fluid passes through said members.

2. A condenser unit for nitric acid vapor, comprising a container of dish form consisting of acid resisting material, having an intake and an outlet for the vapor to be condensed and a trapped outlet in the bottom thereof for the liquid acid; a cover divided into a plurality of parts; a series of condenser-members carried by the cover-parts consisting of coils substantially equal in height to and resting upon the bottom of the container, and having their ends protruding through the cover; inlet and outlet

headers connecting with the opposite ends of the condenser-members and from which a condensing fluid passes through said members.

3. A condenser unit for nitric acid vapor, comprising a container of dish form consisting of acid resisting material, having an intake and an outlet for the vapor to be condensed and a trapped outlet in the bottom thereof for the liquid acid; a cover divided into a plurality of parts; a series of condenser-members carried by the cover-parts consisting of coils substantially equal in height to and resting upon the bottom of the container, and having their ends protruding through the cover; inlet and outlet headers connecting with the opposite ends of the condenser-members and from which a condensing fluid passes through said members; the connection between the headers and coils consisting of nipples carried rigidly by the headers and flexible tubing uniting the nipples to the ends of the coils.

4. A condenser-unit for nitric acid vapor, comprising a container of dish form consisting of acid resisting material having an intake and an outlet for the vapor to be condensed and a trapped outlet in the bottom thereof for the liquid acid; a cover divided into a plurality of parts, a series of condenser-members carried by the cover parts consisting of coils substantially equal in height to and resting upon the bottom of the container, and having their ends protruding through the cover, inlet and outlet headers connecting with the opposite ends of the condenser-members and the connection between the headers and coils consisting of nipples carried rigidly by the headers and flexible tubing uniting the nipples to the ends of the coils, each of the said nipples having a tap.

5. A condenser unit of the type described having a cover divided into independently removable parts, each part having its side edges beveled and the portions near each end formed with holes and having a pair of transverse flanges flanking the holes; a series of condenser-members having their ends protruding through the holes in the cover parts; and cement between the flanges and within the recesses formed by the contiguous beveled edges of the said cover parts.

In testimony whereof I have signed my name to this specification in the presence of two witnesses.

ARTHUR HOUGH.
